UNITED STATES PATENT OFFICE.

HOMER D. CALL, OF SYRACUSE, NEW YORK.

DESIGN FOR A DIE OR SIMILAR ARTICLE.

SPECIFICATION forming part of Design No. 35,962, dated June 17, 1902.

Application filed April 30, 1902. Serial No. 105,405. Term of patent 14 years.

To all whom it may concern:

Be it known that I, HOMER D. CALL, a citizen of the United States, residing at Syracuse, in the county of Onondaga and State of New York, have invented and produced a new and original Design for a Die or Similar Article, of which the following is a specification.

This invention relates to a new and original design for a die or similar article; and it has for its object to provide a design of this character which shall be both useful and ornamental.

The leading feature of the design resides in a circular body provided with a circular field having therein the figures of a butcher's saw, meat-knife, and sharpening-steel grouped in triangular formation and also having the figure of a cleaver disposed within the plane of the said triangular group.

A minor feature of the design is the figures of the meat-knife and sharpening-steel being arranged to constitute the sides of the triangle, with their handle portions disposed next to the figure of the butcher's saw, which latter constitutes the base of the triangular group.

Another minor feature of the design resides in having the figures referred to within a shaded field and also in the body being provided with marginal circular bands surrounding the said shaded field.

In the drawings, Figure 1 is a face view of a die, badge, or similar article embodying the herein-described design. Fig. 2 is a sectional view of the body having the design.

Referring particularly to the figures of the drawings, the numeral 1 designates the circular body of the article. One face (designated by the numeral 2) of the said body is provided thereon with a central circular shaded field 3, having therein the figures of 35 a butcher's saw, meat-knife, and sharpening-steel grouped in triangular formation, with the knife and steel arranged to constitute the sides of the triangle and the handle portions thereof being disposed next to the figure of 40 the saw, which constitutes the base of the triangle. In addition to the figures specified the body is further provided with the figure of a cleaver disposed within the plane of the 45 said triangular group of figures. 50

What I claim is—

The design for a die, or similar article herein shown and described.

In testimony whereof I affix my signature in presence of two witnesses.

HOMER D. CALL.
